COMBINATION CHAIR AND BED

Thomas F. Webster, Madison, N. C.

Application February 10, 1941, Serial No. 378,279

2 Claims. (Cl. 155—45)

This invention relates to a combined folding chair and bed, the primary object of the invention being to provide a device of this character which may be readily and easily converted from a chair to a bed, or vice versa.

An important object of the invention is to provide a device of this character which will be exceptionally light and durable, due consideration having been given to the strength of the frame of the combined chair and bed.

A still further object of the invention is to provide leg members capable of folding upwardly into parallel relation with the side rails of the main frame of the combined chair and bed, thereby providing means for strengthening the seat portion of the device when it is used as a chair.

With the foregoing and other objects in view, which will appear as the description proceeds, the invention resides in the combination and arrangement of parts and in the details of construction hereinafter described and claimed, it being understood that changes in the precise embodiment of the invention herein described, may be made within the scope of what is claimed, without departing from the spirit of the invention.

Referring to the drawings:

Figure 1 is a perspective view of the frame of the device as extended in the formation of a bed.

Figure 2 is a longitudinal sectional view taken on line 2—2 of Figure 1.

Figure 3 is a sectional view taken on line 3—3 of Figure 1.

Figure 4 is a perspective view of one of the latch members used in holding the leg members in their extended or supporting positions.

Figure 5 is a perspective view of the frames moved with respect to each other, to provide a chair.

Figure 6 is a side elevational view thereof illustrating the flexible seat portion or cover.

Figure 7 is a sectional view taken on line 7—7 of Figure 8.

Figure 8 is a sectional view taken on line 8—8 of Figure 7.

Figure 9 is a fragmental perspective view illustrating one end of one of the frames, the view illustrating the end of the frame in its inverted position.

Referring to the drawings in detail, the convertible chair and bed comprises an outer frame 5 and an inner frame 6, the outer frame embodying spaced parallel side rails 7, connected at one of their respective ends by means of the transverse rail 8. A rod indicated at 9 also connects the side rails 7, at a point adjacent to the rail 8.

The inner frame also comprises spaced parallel side bars 10 and 11 connected at the outer end of the frame by means of the bar 12 and rod 13.

Extending longitudinally of the side rails 7 of the outer frame 5, are bayonet slots 14, the right angled ends 15 thereof being disposed towards the outer end of the frame 5.

Pins 16 extend outwardly from the rails 10 and 11 of the inner frame, and are disposed an appreciable distance from the inner ends of the rails 10 and 11, as clearly shown by Figure 1 of the drawings. These pins are formed with shanks 18 that are square in cross section, so that they fit within the slots 14 with a sliding movement. When these pins are moved to the desired positions, within the slots, it will be seen that pivotal movement of one frame with respect to the other will be prevented, thereby insuring against the device collapsing, when in the formation of a chair, or bed. In order to further secure the frames against collapsing, when the device is converted into a bed, pins 19 are provided and extend through registering openings in the adjacent side rails of the frames, as clearly shown by Figure 3 of the drawings. These pins 19 are preferably supported on spring arms 20 and are provided with finger pieces 21, so that the pins may be readily manipulated, should it be desired to slide the sections or frames with respect to each other to convert the bed into a chair.

At the outer end of each frame, are legs 22, the legs being connected by a transverse bar 23. The upper ends of the legs 22 are formed with openings for the reception of the rods 24 that have their ends secured in the side rails of the frames, the rods 24 providing supports for the legs, whereby the legs may be swung upwardly from their vertical positions as shown by Figure 1 of the drawings, to their inactive positions in parallel relation with the side rails of the frames, as shown by Figure 5 of the drawings.

In order that the legs will be secured in their upright or supporting positions, latch members indicated at 25 are provided, and extend through the bars 8, the inner ends of the latch members being formed with heads 26 adapted to be swung upwardly into engagement with the bars 23, holding the bars against movement.

When the legs 22 are swung upwardly to the positions as shown by Figure 5 of the drawings, the latch members are turned so that the ends thereof will provide rests for the leg members.

The reference character 27 designates the flexible strip, constructed preferably of canvas, that has one of its ends secured around the rod 9.

at one end of the outer frame 5, the opposite end of the flexible strip being extended over the rod 13 connecting the outer ends of the inner frame, from where it passes downwardly over the transverse bar 23 of the leg members which now form a part of the back section of the chair, as clearly shown by Figure 6 of the drawings. Fasteners indicated at 28, which are of the head and socket type, are secured adjacent to the upper free end of the flexible strip, and are secured when the flexible strip is positioned to provide a chair. The socket members 29 which are secured adjacent to the free end of the flexible strip, are now secured to the heads 30 secured to the flexible strip an appreciable distance from the upper end thereof.

When the frames are extended to form a bed as shown by Figure 2 of the drawings, the fasteners 28 and 29 are disconnected, and the loop formed at the upper end of the flexible strip, is now positioned over the rod 13 at one end of the bed, and the socket members of the fasteners 28 are positioned over the heads 31 of the fasteners which are spaced appreciable distances from the end of the flexible member. In this position, the flexible member forms a yieldable bed bottom.

In view of the foregoing detailed disclosure, a further disclosure as to the operation of the

convertible chair and bed, is believed to be unnecessary.

What is claimed is:

1. A convertible chair and bed comprising substantially U-shaped inner and outer frames, said frames embodying side rails, the side rails of the outer frame having bayonet slots and fitted in contacting parallel relation with the side rails of the inner frame, outwardly extended pins secured to the inner frame and disposed within the slots, said pins being square in cross section and adapted to slidably engage the walls of the slots holding the frames against pivotal movement with respect to each other, leg members pivotally connected to the frames, and a flexible cover for the frames.

2. A convertible chair and bed, comprising pivotally connected outer and inner frames, said frames including side rails, certain of said rails having longitudinally disposed slots formed with right angled ends, pins having square shanks, extending from the others of said side rails and disposed in the slots, said pins adapted to move into the right angled ends of said slots engaging the walls of the slots and preventing pivotal movement of the sections with respect to each other when the frames are moved to provide a chair, and a flexible cover for said frames.

THOMAS F. WEBSTER.
